(57) **CLAIM**

The ornamental design for a whole blood separator device, as shown and described.

DESCRIPTION

FIG. 1 is a perspective view of a whole blood separator device showing our new design;

FIG. 2 is a left side view thereof;

FIG. 3 is a right side view thereof;

FIG. 4 is a top plan view thereof; and,

FIG. 5 is a bottom plan view thereof.

The broken lines depict environmental subject matter and form no part of the claimed design.
